UNITED STATES PATENT OFFICE

156,713

ANTIRATTLER FOR AUTOMOBILE WINDOWS

Paul R. Engel, Rochester, N. Y., assignor to Carl Wirth & Son, Inc., Rochester, N. Y., a corporation of New York

Application November 23, 1948, Serial No. 149,786

Term of patent 14 years

(Cl. D10—10)

To all whom it may concern:

Be it known that I, Paul R. Engel, a citizen of the United States, residing at Rochester, in the county of Monroe and State of New York, have invented a new, original, and ornamental Design for an Antirattler for Automobile Windows, of which the following is a specification, reference being had to the accompanying drawing, forming part thereof.

Fig. 1 is a top plan view of an antirattler for automobile windows, showing my new design;

Fig. 2 is an end elevational view; and

Fig. 3 is a side elevational view thereof.

I claim:

The ornamental design for an antirattler for automobile windows, as shown.

PAUL R. ENGEL.
